SUPPORTING CLIP FOR FLOWER
POTS OR THE LIKEJoyce E. Brown, Playa Del Rey, Calif., assignor to C.I.I., Inc., Whittier, Calif.

Filed Dec. 29, 1972, Ser. No. 319,628

Term of patent 14 years

Int. Cl. D8—08

U.S. Cl. D8—257

FIG. 1.

FIG. 2.

FIG. 4.

FIG. 3.

FIG. 5.

FIG. 1 is a perspective view of a supporting clip for flower pots or the like illustrating my new design as it appears looking toward the front portion of the clip;

FIG. 2 is a side elevational view of the supporting clip;

FIG. 3 is a rear view of the supporting clip;

FIG. 4 is a top view thereof; and

FIG. 5 is a bottom view thereof.

I claim:

The ornamental design for a supporting clip for flower pots or the like, as shown.
